CIGARETTE HOLDER

Philip F. Havey, Washington, D. C.

Application December 19, 1938, Serial No. 246,690

2 Claims. (Cl. 131—259)

This invention relates to a holder for a cigarette or the like and it aims to provide a novel means thereon to coact with a finger ring in order to be held in place and positioned by the latter in combination with the finger on which the ring is worn.

Another object is to provide such a holder as may be engaged or disengaged with the finger ring at will and wherein the novel means most 10 advantageously positions or locates the cigarette or the like so as to not interfere with the fingers or their substantially natural position even in the presence of the holder.

Another object is to provide such a construction having an attaching stem and a cigarette holder or clasp member thereon, and movable relatively to the stem to release or clasp the cigarette and thereby facilitate not only its insertion but also the removal of a cigarette butt 20 merely by shaking it from the holder.

The more specific objects and advantages will become apparent and in part be pointed out in the description following taken in connection with accompanying drawing, illustrating an operative 25 embodiment.

In said drawing:

Figure 1 is a view in perspective showing the invention in use;

Figure 2 is a view in elevation showing the 30 improved holder;

Figure 3 is an enlarged longitudinal sectional view taken on the line 3—3 of Figure 2;

Figure 4 is a longitudinal sectional view taken on the line 4—4 of Figure 3;

Figure 5 is a horizontal sectional view taken 35 on the line 5—5 of Figure 2, and

Figure 6 is a vertical sectional view similar to Figure 4, but with the clasp extended or projected from the stem.

Referring specifically to the drawing, wherein like reference characters designate like or similar parts throughout the different views, 10 designates a fine or elongated stem which may be straight, curved or of any other desired configuration.

Said stem is adapted to be disposed between a finger 11 of a hand of the smoker and a ring 12 thereon, and in order to minimize danger of accidental turning on the hand, stem 10 is terminally curved as at 13 to conform to the adjacent curvature of the finger 11. Obviously, this stem may be of any cross sectional configuration, for instance, round, flat, polygonal or otherwise. In addition, such stem 10 may be made from any preferred material, for instance, gold, silver, 55

platinum, aluminum, brass, copper, acetate, synthetic resins and plastic materials, generally.

At one end, said stem has a substantially U-shaped portion 14 and in the concavity thereof, it is lined with an arcuate strip 15 of metal or other material united to the portion 14. While the arcuate strip may be of some other material than that of the stem 10 and the U-shaped portion 14 and may be united thereto by any suitable means, in the preferred form of this invention 10 it is merely an arc or grooved recess in the portion 14 itself. The purpose of this arcuate strip 15 is to provide a recess in which the lower portion of the jaws 19 can be retained when the holder is in use, thus providing a smooth contour 15 for the stem and holder and a firm foundation that will aid in preventing trembling and torsion of the holder when in smoking position. Said stem 10 has a longitudinal recess 16 which opens at 17 through the lining 15 into the space of the 20 portion 14.

A clasp or holder generally designated 17A is employed for a cigarette or the equivalent shown at 18 in Figure 1. This clasp has opposite concave jaws 19 disconnected at their upper ends 25 but connected at their lower ends by an expansive U-shaped spring portion 20 which is normally contained entirely within the recess 16 as shown in Figure 4. The upper portion of the U-shaped spring 20 is wider than the recess 16. 30 When the holder 17A is projected, the jaws 19 are separated to the maximum extent as shown in Figure 6, in which position a cigarette is insertable or a butt is removed. After insertion of a cigarette between the jaws 19 in the position of Figure 6, such holder 17A is depressed into the position of Figures 1, 2 and 4, thereby contracting the spring 20 at the upper end and causing the jaws 19 to contract about or clamp the cigarette. The said spring 20 and jaws 19 are preferably 40 made of resilient metal and the jaws 19 have additions or enlargements 21 at their upper portions, of the same material as the stem 10, and serving as extensions of the U-shaped portion 14, particularly enabling notches to be provided 45 therein as at 22.

The holder 17A may be extended or retracted relatively to the stem 10 by manipulation of the fingers engaged in the notches 22. In fact, the entire holder 17A may be detached or removed 50 from the stem 10, if desired. However, as shown, a pin 23 is located within and fastened by soldering 26 or otherwise to the spring 20, passing slidably through elongated slots 24 in the stem, and at opposite ends having heads or slides 25 55

fastened thereto. Such slides 25, as shown in Figure 3, normally close the slots 24, and they also form means manually engageable in order to project the holder 17A, through movement 5 of the ring 23 to the extent permitted by slots 24.

It will be observed from Figure 1, that the article is retained by the ring 12 and finger 11, with the cigarette in a position facilitating the smoking thereof and enabling natural position-10 ing of the fingers. The smoker may move his arm from time to time, with slight effort to shake ashes from the cigarette. At the same time, the device is readily applicable and removable through minimum effort.

15 In order to eliminate danger of accidental turning or torsion of the holder 17A, relatively to the stem 10, one of the adjacent parts may have a projection 27 and the other have a recess 28 to receive the same in cigarette-clamping 20 position and as specifically shown, projection 27 is carried by one of the members 21 while recess 28 is provided on the member 14.

Various changes may be resorted to provided they fall within the spirit and scope of the invention.

25 I claim:

1. In an article of the class described, a holder for a cigarette having a stem projecting from said holder means, said stem being adapted to be inserted through a ring on the finger of the user, and said stem being curved slightly at the

outer end to conform to the knuckle of the user's hand so that when the stem is inserted through the ring, the curved end fits tightly over the knuckle forming a prop to hold the stem taut regardless of the movement of the fingers or 5 hand of the user.

2. In a cigarette holder, a support comprising a bifurcated portion and a stem recess of arcuate formation in the bifurcated portion, a slot in the stem communicating with the recess, the side 10 walls of the slot being slotted, a pin slidably mounted in the slot, a U-shaped spring clamp secured to the pin and slidably mounted in the stem slot, said clamp having portions adjacent the free end thereof of substantially semicircular 15 shape and adapted to fit within the recesses, the inner surfaces of the semicircular portions being adapted to lie in flush relation with adjacent interior surfaces of the arcuate portion of the stem recess, and arcuate members having in-20terior recesses secured to the ends of the semicircular portions of the clamp, the interior surfaces of the arcuate members being flush with adjacent interior surfaces of the semicircular portions of the clamp whereby when the cigarette 25 is placed within the arcuate portions of the clamp or portions of the recess of the arcuate members, the portion of the cigarette held therein will be in contacting relation with an adjacent portion of all the arcuate members. 30

PHILIP F. HAVEY.
